UNITED STATES PATENT OFFICE.

JOHN C. MERWIN, OF HOLYOKE, MASSACHUSETTS, ASSIGNOR TO NATIONAL BLANK BOOK COMPANY, OF HOLYOKE, MASSACHUSETTS, A CORPORATION OF MASSACHUSETTS.

LOOSE-LEAF BINDER.

1,084,159.

Specification of Letters Patent. Patented Jan. 13, 1914.

Application filed May 10, 1913. Serial No. 766,668.

To all whom it may concern:

Be it known that I, JOHN C. MERWIN, a citizen of the United States, residing in the city of Holyoke, county of Hampden, State of Massachusetts, have invented certain new and useful Improvements in Loose-Leaf Binders; and I do declare the following to be a full, clear, and exact description of the invention, such as will enable others skilled in the art to which it appertains to make and use the same.

My invention has reference to loose leaf binders which are in the form of a book and in which complementary hook elements are provided which may be opened or closed as the occasion may demand.

The main object of the present invention is to provide a simple and effective means readily manipulated whereby the various hook elements may be simultaneously opened without any pressure applied at the back of the book, a further object of my improvement being to secure the device in position within a book back in a very simple manner and without the use of any tools whatever.

With these ends in view my invention consists in the various constructions and arrangements hereinafter fully described and then particularly pointed out in the claims which conclude this description.

In the accompanying drawing Figure 1 is a front elevation of my improvement, Fig. 2 a rear elevation, Fig. 3 a section at the line α , α , of Fig. 2, Fig. 4 a detail interior elevation of the spring cover plate, Fig. 5 a detail interior view of the metal back which is attached to the book, Fig. 6 an end elevation of my improvement, and Fig. 7 a side elevation, partly in section, of my improvement as it appears when assembled within the metal back.

Similar numerals of reference denote like parts in the several figures of the drawing.

1 is the cover plate which is made of sheet metal of a general trough-like shape having end portions 2 which act as closures for the cover plate, said portions being pierced to provide slots 3 for the purpose presently to be explained.

Within the cover plate are assembled elongated flat strips 4, 5, which carry the complementary hook members 6, 7, these hooks extending through perforations 8, 9, in the cover plate in the usual manner. These

strips are hinged together at their meeting edges by means of small tongues 10, 11, which extend from one strip on opposite sides of the other strip, and ears 12, 13, formed integral with the cover plate are turned inwardly so as to lie across the faces of the strips and prevent the latter from falling away from said plate. These strips when hinged together in the manner above described are at a slight angle as shown more particularly at Fig. 3, and the closing of the hooks will force the strips downwardly until they have passed below a horizontal plane, the spring nature of the cover plate permitting this. After the hooks have been closed and the strips at their hinged edges brought below a horizontal plane the resiliency of the cover plate will keep the parts locked in this position. When the hooks are opened the cover plate will yield until these strips at their hinged edges have been forced above the horizontal plane, the resiliency of said plate then acting to lock the parts in this condition. This action of the strips and hooks is not new but is characteristic of all loose leaf binders which employ hinged strips of this sort that carry the hook members.

Various devices have been heretofore employed for opening all the hooks simultaneously by means of a pressure brought to bear against the strips, but these devices mainly contemplate a push button in the back of the book or are associated directly with the back plate that is attached to the book cover.

My present invention aims particularly to provide devices in plain sight in the upper surface of the outside or cover plate of the binder so that by depressing these devices the hooks will all open simultaneously, and these devices consist of levers 14, 15, which extend loosely through openings 16, 17, in the cover plate and are pivotally connected at the inside of said plate by means of lugs 18, 19, that are integral with said plate and are forced inwardly within recessed portions 20, 21, formed within the levers. The inner extremities of these levers 14, 15, beyond their pivotal points are immediately beneath the strips 4, 5, while the outer ends of the levers that project above the cover plate are formed into horizontally disposed buttons 22, 23. In operating my improvement these buttons are depressed which will cause

the inner extremities of the levers to be forced upwardly against the strips 4, 5, and thereby operate them to effect the opening of the hooks.

5 I provide a metal back 24 which is secured in any suitable manner to the book back, and this metal back has upstanding inwardly turned lugs 25; and my improvement is simply attached in position by springing these 10 lugs within the slots 3 at the ends of the cover plate.

It will be clear from the above description that pressure is applied directly against the buttons 22, 23, at the top of the cover plate 15 in order to open the hook members, and that the hooks will all open simultaneously when such pressure is applied.

By merely releasing the spring lug 25 from the openings 3, the cover plate and all 20 the operative parts of the binder may be removed bodily without disturbing the back plate 24, and this is a decided advantage in that an entire book of loose leaves in their bound condition may be bodily transferred 25 to other binder covers. Also, if necessary, different cover plates may be substituted carrying a greater or lesser number of prong hooks, by merely removing a cover plate and substituting therefor the plate desired.

30 Having thus described my invention what I claim as new and desire to secure by Letters Patent is:—

1. In a loose leaf binder, the combination 35 of a book back, a metal back plate secured to said book back, a sheet metal cover plate having resilient sides and detachably secured to said back plate, and operative parts including elongated flat strips confined between said resilient sides and pivoted together at their 40 inner edges and carrying complementary ring sections and devices for opening the

same, all connected together and carried by said cover plate.

2. In a loose leaf binder, the combination 15 of a book back, a metal back plate secured to said book back, a sheet metal outside cover plate having resilient sides and detachably secured to said back plate, elongated flat strips pivotally connected at their abutting edges and confined between said 50 sides, complementary ring sections carried by said strips, and levers pivotally supported by said cover plate with their inner extremities extending immediately beneath said strips, said levers projecting upwardly 55 through the cover plate and provided with push buttons outside said plate.

3. In a loose leaf binder, the combination 60 of a sheet metal cover plate having resilient sides, elongated flat strips confined between 65 said sides and pivotally connected at their abutting edges, complementary ring sections carried by said strips, levers pivotally supported by said cover plate with their upper extremities extending through and above the same while their lower extremities extend immediately beneath the pivoted edges 70 of said strips, and a back plate secured to the book back to which back plate said cover plate is detachably connected.

4. The combination of the cover plate having inwardly turned ends provided with slots, of the metal back plate having upstanding inwardly turned lugs adapted to be sprung within said slots.

In testimony whereof I affix my signature in presence of two witnesses.

JOHN C. MERWIN.
